DESIGN FOR A DOOR PULL

William F. Vernon, Newton, Iowa

Application August 24, 1939, Serial No. 86,861

Term of patent 14 years

To all whom it may concern:

Be it known that I, William F. Vernon, a citizen of the United States and a resident of Newton, in the county of Jasper and State of Iowa, have invented a new, original, and ornamental Design for a Door Pull, of which the following is a specification, reference being had to the accompanying drawing, forming part thereof.

Fig. 1 is a front elevational view;
Fig. 2 is an end elevational view; and
Fig. 3 is a top plan view of a door pull, showing my new design.

I claim:
The ornamental design for a door pull, as shown.

WILLIAM F. VERNON.
